CLAIM

The ornamental design for a case for radio and battery, as shown and described.

DESCRIPTION

FIG. 1 is a top, front and left side perspective view of a case for a radio and battery showing my new design;

FIG. 2 is an exploded top, front and right side perspective view thereof;

FIG. 3 is an exploded right side elevational view thereof;

FIG. 4 is an exploded rear elevational view thereof; and

FIG. 5 is a bottom plan view thereof.
The broken line showing of the battery is for illustrative purposes only and forms no part of the claimed design.

FIG. 1.

FIG. 2.

FIG. 5.
